UNITED STATES PATENT OFFICE.

SYDNEY C. NOTT, OF CHICAGO, ILLINOIS, ASSIGNOR TO SIEBER & TRUSSELL MANUFACTURING COMPANY, A CORPORATION OF MISSOURI.

LOOSE-LEAF BINDER.

No. 829,225.

Specification of Letters Patent.

Patented Aug. 21, 1906.

Application filed May 14, 1904. Serial No. 208,052.

To all whom it may concern:

Be it known that I, SYDNEY C. NOTT, a citizen of the United States, and a resident of Chicago, Cook county, Illinois, have invented certain new and useful Improvements in Loose-Leaf Binders; and I do hereby declare that the following is a full, clear, and exact description of the same, reference being had to the accompanying drawings, and to the letters of reference marked thereon, which form a part of this specification.

This invention relates to improvements in loose-leaf binders of that class adapted to receive and hold removable sheets and adapted to be adjusted to admit of varying the capacity of the binder at will. Heretofore the capacity of loose-leaf binders has usually been limited and capable of but slight expansion, and usually considerable space in the binder is not available for use inasmuch as the insertion or removal of sheets necessitated the insertion of the fingers between the back edges of the sheets. The capacity of such devices has also been confined within comparatively narrow limits, owing to the inability to secure sufficient rigidity of the binding devices when extended beyond their normal limit.

The object of this invention is to provide a loose-leaf binder adapted to afford a construction capable of being expanded to any desired extent and affording positive means for locking either a single sheet in place or any desired number of sheets.

It is a further object to provide an auxiliary clamping-plate adapted for adjustment entirely independently of the quantity of or number of sheets in the binder and acting to rigidly clamp the same entirely independently of the width of the back of the binder.

It is also an object to afford a closed sectional back for the binder adapted to be varied in width by the insertion or removal of sections and so constructed as to afford automatic locking means at each end of the back.

The invention embraces many novel features; and it consists in the matters herein-after described, and more fully pointed out and defined in the appended claims.

In the drawings, Figure 1 is a front elevation, partly in section, of the back or frame of the binder with the covers removed, showing the back as a single section. Fig. 2 is a section taken on line 2 2 of Fig. 1. Fig. 3 is

a section taken on line 3 3 of Fig. 1 and showing means for attaching a cover. Fig. 4 is a section taken on line 4 4 of Fig. 1. Fig. 5 is a similar view showing the upper and lower binding-plates separated. Fig. 6 is a section taken on line 6 6 of Fig. 4. Fig. 7 is a detail of the central binding-screw, showing a slight modification thereof. Fig. 8 is a fragmentary top plan view of the cover and means for attaching the same to the binder-back. Fig. 9 is a bottom plan view of the same. Fig. 10 is a section taken on line 10 10 of Fig. 8. Fig. 11 is a transverse section of one of the removable back-sections, showing a rounded back thereon. Fig. 12 is a detail of the clamping bolt and nut. Fig. 13 is a transverse section of the binder-frame, illustrating the latch construction, showing the binder in its open position. Fig. 14 is a front view of the same, showing the binder closed. Fig. 15 is a front elevation of the binder frame and back, showing the same expanded by the addition of removable back-sections and the upper clamping-plate partly removed. Fig. 16 is a section taken on line 16 16 of Fig. 15. Fig. 17 is a section taken on line 17 17 of Fig. 15. Fig. 18 is a detail view of one of the sections of the sectional posts. Fig. 19 is a perspective view of the central removable back-section having a nut thereon for the clamping-bolt. Fig. 20 is a similar view of a central removable back-section with the nut omitted.

Referring first to Figs. 1 to 12, inclusive, the binder is shown in its most contracted form or that adapted to contain a minimum quantity of the leaves or sheets and comprises, as shown, a strap or plate A, which affords the bottom clamping or binder plate of the frame and to which is attached the bottom cover. An upper binding or clamping plate A' corresponds with said bottom binding-plate A. Intermediate the said binding-plates A A' is provided a back-section a, provided at each end with an inturned flange a', adapted to afford a part of the ends of the binder-frame. Said upper binding-plate A' is bent longitudinally to afford a depending back-flange a'', which extends downwardly along the back-section a and is approximately of the same width therewith. At each end of said upper binding-plate A' is provided an end plate a'', which fits over the end flanges a' of the back a, and a pin a', carried thereon, extends

through a vertical slot in the inwardly-turned end or flanges a' of the back-section, as shown in Figs: 4 and 5, and permits the binding-plates to be drawn apart. Adjacent 5 each end of the back-section a a clip or bracket a^5 is secured, comprising a strap of sheet metal bent to afford a cylindric bulb provided with a cylindric seat or bore extending transversely and parallel with the 10 plane of said back-section and supported at a distance therefrom and secured to the back plate by means of rivets or the like, as shown in Fig. 2, engaged through the outturned ends of the strap and the back. Secured on 15 the top binding-plate A' are downwardly-extending tubular impaling-posts B , which register with the bore of said brackets a^5 . As shown, each of said impaling-posts contains a coiled spring b , which bears against the inner 20 end of a post-section b' , which is brazed or otherwise secured in the brackets a^5 and is threaded at its outer end and extends through the binding-plate A and is provided on the outer end thereof with an angular nut b^2 . A 25 threaded clamping-bolt C extends through the upper binding-plate A' and is provided on the outer side with an angular head c and at the point where engaged in said binding-plate is of smaller diameter and engaged rotatively 30 in place by a slotted plate c^3 , riveted to the plate A' . The lower end of the clamping-bolt is provided with a reversely-threaded extension c' of smaller diameter, as shown in Fig. 1, adapted to engage in a nut c^2 , secured 35 to and beneath the binding-plate A . As shown in Fig. 12, said nut is transversely notched on opposite sides and said extension c' is flattened on opposite sides, so that when 40 said bolt is turned into one of its adjusted positions it can be readily pressed inwardly, partly through said nut, until the sheets are engaged and may be then set up by rotating the same into engagement with the threads of the nut. Secured within the back frame 45 thus formed is a follower or clamping-plate D , of metal, flanged on its upper side to afford sufficient rigidity and strength and notched at each end to receive the cylindric heads of the brackets a^5 . Said clamping-plate or follower 50 is provided with a central nut d , which engages the threads of the bolt when assembled, so that rotation of the clamping-bolt in one direction acts to move the clamping-plate D downwardly toward the bottom binding-plate A , pressing the leaves or sheets 55 contained in the binder upon the same, while rotation in the other direction releases and acts to move said clamping-plate D upwardly to release the pressure from the 60 sheets. Inasmuch as the spring b acts to force the binding-plates A and A' apart when said clamping-bolt C is reversed, slight movement of said bolt is sufficient to engage or release the sheets. Should it be desired to increase 65 the capacity of the binder, the top

binding-plate A' , with its back a^2 , and the lower back-section a are released from the lower plate A by the removal of the nuts b^2 from the post-sections and longer or additional post-sections secured in place, which 70 may be of any desired length. Additional back sections E and E' are secured on the sectional or other posts e' , which pass through clips e thereon, corresponding and of uniform diameter with the clips a^5 and affording a 75 cylindric standard or rib rigidly braced on each back-section and extending across the back of the frame near each end thereof. The section E' is secured upon the bottom binding-plate, and the plate E is secured in a 80 similar manner thereon. The removable back-section E is provided centrally with a clip or bracket e^2 , corresponding with the brackets or clip e or a^5 and provided with internal screw-threads adapted to receive the 85 reversely-threaded extension c' of the clamping-bolt C , thus enabling the back frame to be extended to any desired width, while providing a solid or closed back for the book and rigid standard or rib to engage the paper. 90 The follower or clamping-plate D operates as before described, moving upwardly or downwardly on the clamping-bolt C and exerting clamp-pressure upon the leaves or releasing the same, dependent upon the direction of 95 the rotation thereof.

As shown in Fig. 13, latches may be provided at each end of the binder-frame, comprising a leaf-spring formed of a strip or plate of spring-steel or other suitable material F , rigidly secured on the end a^3 of the upper binding-plate and provided with a bolt f , which extends into a notch in the section a' when the binder is closed. Said latches are 100 so arranged that when the upper binding-plate is drawn away from the lower plate to its farthest extent in opening the binder said bolts engage above the upper margin of the inturned end a' and hold the binder in open position, even should the spring b in the tubular portions of the post be omitted. The 105 under side of the bolt f is inclined to permit the upper binding-plates to be forced downwardly to close the binder. The latch F springs at once into locking engagement in 110 the notch in the end a' when approximately the desired pressure is secured.

For the purpose of holding a portion of the leaves in place while inserting new leaves the brackets e e^2 of the back-section E and the 115 ends of said section are apertured in alignment to receive a rod G , which extends through the said brackets at the rear of the head of the same and engages the pile of sheets near their inner edge and acts to hold the 120 greater part of the same from disarrangement when inserting or removing leaves, as shown in Fig. 16.

Obviously the covers may be secured on said binder in a variety of ways. As shown, 130

a strip of any suitable material H is secured upon each of the binding-plates and is apertured to afford access to the nuts b² and to the head c of the bolt C. The binding material, such as leather or other suitable material h and h', is wrapped around said strips and extends forwardly on each side of the cover-board h² in the usual manner, affording a desired finish. Should it be desired to afford a round back for the volume, one or more removable back-sections E² are provided on the rear face thereof with a convex strip e², affording the desired convexity for the back.

- 15 The operation is as follows: The binder is adjusted, as shown in Fig. 1, for a minimum quantity of the leaves to be secured therein, and it is obviously easy to rotate the bolt C before engaging the same in the nut of the bottom binding-plate sufficiently to move the follower or clamping-plate downwardly into position to engage even a single sheet should the same be inserted in the binder. It is also obvious that said follower or clamping-plate can be adjusted to engage any desired number of sheets within the full capacity of the binder, as shown in Fig. 1, by varying the position upon the screw-shaft before closing the binder. When the binder is full, 30 as shown in Fig. 1, one or more back-sections may be inserted, as before described, forming a back of any desired width, having rigid standards of uniform size to be engaged by the paper. Inasmuch as the clamping-plate 35 can be adjusted, as before described, either a quantity of leaves but slightly greater than those before contained in the device or sufficient to fill the entire binder may be engaged in place.
- 40 The spring b in the tubular post B is not essential, as it is obvious that the spring-latches F will serve to support the upper binding-plate when the binder is unlocked for the insertion or removal of leaves and that downward pressure on said binding-plate will act to close the same by permitting the bolts of said latches to snap into suitable notches in the end plate in the back-section a. The construction described affords a 45 minimum and a maximum capacity beyond that possible for any other extensible post-binder and affords ready means for adjustment of the clamping pressure without relative movement of the upper and lower binding-plates. The use of the rod G enables a 50 portion of the leaves to be held from relative movement when the binder is unlocked, thus enabling the operator to insert new leaves with the use of one hand only. The 55 tubular section B of the binding-post may be secured in any desired manner on the binding-plates A'. As shown, however, said plates are apertured to receive the ends of said binding-posts, which are upset and expanded 60 within said plate and the outwardly-project-

ing ends thereof are cleft and turned over, as shown in Figs. 8 and 15.

I have described but one of several constructions embodying my invention. I therefore do not purpose herein limiting myself otherwise than is necessitated by the prior art and as stated in the claims, as obviously many details of construction may be varied without departing from the principles of this invention.

75

I claim as my invention—

1. A loose-leaf binder comprising an expandable frame provided with a back, an extensible post therein comprising telescoping sections, a longitudinal web on one of said sections adapted to support said post from the back of the frame, a threaded extension on said section projecting through the side of the frame, and a nut adapted to engage said extension.

85

2. An expandable loose-leaf binder comprising binding-plates, extensible posts connecting said plates, removable back-sections and interfitting parts carried on the back-sections and insertible in one member of said extensible posts for further lengthening the same.

90

3. A loose-leaf binder comprising upper and lower, relatively adjustable binding-plates, a back in said binder, impaling-posts carried on said binding-plates, means directly connecting portions of said posts to said back, a rotative threaded clamping-bolt journaled in the upper binding-plate and a follower-plate within the binder having threaded engagement with said clamping-bolt and acting to afford compression of the contents of the binder both simultaneously with and independently of the adjustment of the binding-plates.

105

4. In a loose-leaf binder a frame comprising upper and lower binding-plates and an extensible back thereon, adjustable impaling-posts engaged on said plates, connecting members connecting portions of the posts with said back, a bolt journaled in one of said binding-plates and having portions thereof reversely threaded, a nut carried on said frame in position to engage one of the threaded portions of said bolt and a follower or clamping-plate carried on the other threaded portion of said bolt and movable into and out of compressing relation with the contents of the binder by rotation of said bolt.

110

5. A loose-leaf binder comprising upper and lower binding-plates, one of which is provided on its rear margin with a back-flange, removable back-sections adapted to be engaged between said binding-plates and affording a closed back therefor, extensible posts carried on one of said plates and on which said back-sections are secured, a rotative clamping-bolt carried on one of the binding-plates, a fixed nut supported upon the back in alinement with the lower end of

120

125

130

- 1 said bolt and adapted to engage the same and adjust the binding-plates to which said bolt is connected, a follower or clamping-plate threaded on said bolt and movable into 5 and out of compressing relation with the sheets when said bolt is turned and spring-latches acting to automatically lock said binding-plates from movement with respect to each other.
- 10 6. A back-section for a loose-leaf binder comprising a metallic strip of any desired width, inwardly-directed brackets thereon provided with cylindric apertured bulbs and an internally-threaded bracket on the inner 15 face of said strip.
7. A back-section for a loose-leaf binder comprising a strip of metal having inwardly-directed end portions, and brackets on said strip having apertured cylindrical bulbs 20 adapted to engage the sheets.
8. A loose-leaf binder comprising in combination with the compressing elements and adjustable impaling-posts, a rod adapted to be inserted between the leaves at the back of 25 the impaling-posts and acting to hold a portion of said leaves under compression during the adjustment of said posts and the insertion or removal of other leaves.
9. In an expansible loose-leaf binder, 30 means for holding loose leaves therein and a rod adapted to be inserted between the rear edges of the leaves acting to hold a portion of the same under compression while the binder is being expanded.
- 35 10. In an expansible binder, binding-plates, a closed back between the same, impaling-posts carried on said plates, means 40 bracing the same with the back and a rod adapted to be inserted between the leaves back of the impaling-posts.
11. In a loose-leaf binder the combination with movable binding-plates, of an auxiliary compression-plate or follower therebetween, a right and left threaded screw, journaled in 45 one of said binding-plates, and operatively engaged on said compression-plate, and acting to force the compression-plate inwardly with the binding-plate to which it is attached, when the latter is operated by hand, and 50 means carried in alignment with the inner end of said screw and adapted to engage the same and force the compression-plate inwardly after the binding-plate has reached the limit of its above-mentioned movement.
- 55 12. In a loose-leaf binder, the combination with the binding-plates and impaling-posts of a rotative threaded shaft on one of said plates comprising right and left threaded portions, that at the inner end of the bolt, 60 being mutilated, a mutilated nut complementary with the mutilated end of the shaft and adapted to permit the same to be pressed inwardly therethrough and an auxiliary compression-plate on the other portion of said bolt, said portions operating by rotation of 65
- the bolt to draw the binder together and to move the follower into compressing relation with the sheets.
13. A loose-leaf binder comprising binding-plates, extensible posts connecting said 70 plates, one member of each of which is sectional, a sectional closed back and brackets rigidly secured on the back and having apertured cylindric bulbs through which the sectional portions of said posts extend, said 75 bulbs affording a continuous rib or standard of uniform size at each end of the binder adapted for engagement by the sheets.
14. In a loose-leaf binder comprising binding-plates and impaling-posts, a clamping-bolt adapted for engagement in each binding-plate, and a follower or clamping-plate having threaded engagement therewith and acting to engage the sheets.
15. In an expansible binder, an upper and 80 a lower binding-plate, a sectional closed back connecting said plates, a right and left threaded screw journaled in the upper binding-plate, a follower having threaded engagement thereon adapted to be raised and lowered with said upper binding-plate and a nut carried on said back beneath the screw and adapted to engage the lower end of said 85 screw.
16. In a loose-leaf binder, a telescoping 90 sectional back, binding-plates thereon movable to and from each other, a follower-plate, a screw adapted to adjust said follower with respect to one of said plates and a nut carried on the back below said screw adapted to engage the same.
17. In a loose-leaf binder the combination with binding-plates, of telescoping end sections thereon adapting said plates for adjustment with respect to each other, telescoping 95 impaling-posts on said plates, a follower intermediate said binding-plates and adapted to be moved with one of the same, a screw journaled in one of said plates and connected with said follower and provided with a reduced inner end threaded oppositely from the remaining portion of the screw and screw-threaded means supported on the binder in alignment with said screw and adapted to engage said reduced end and hold the binding- 100 plates in adjusted position.
18. In an extensible loose-leaf binder, in combination, a back plate provided with means for engaging a side plate, a side plate adapted for engagement with such back 110 plate, and an extension back plate adapted to be interposed between the first-named back plate and the side plate.
19. A back-section for loose-leaf binders comprising a plate, and a bracket rising from 115 the plate and formed of a sheet of metal folded upon itself and enlarged at its fold to form a tubular leaf-holding rod.
20. A loose-leaf binder comprising an 120 expansible frame provided with a back, an ex- 125

tensible post therein comprising telescoping sections, a longitudinal web on one of said sections adapted to support said post from the back of the frame, a threaded extension 5 on said section projecting through the side of the frame, and a threaded retaining member adapted to engage said extension.

In testimony whereof I have hereunto subscribed my name in the presence of two subscribing witnesses.
